US00D856991S

(12) **United States Design Patent** (10) **Patent No.:** **US D856,991 S**
(45) **Date of Patent:** **** Aug. 20, 2019**

(54) **OVERLAY**

(71) Applicant: **Belkin International, Inc.**, Playa Vista, CA (US)

(72) Inventor: **John F. Wadsworth**, Burbank, CA (US)

(73) Assignee: **Belkin International, Inc.**, Playa Vista, CA (US)

(**) Term: **15 Years**

(21) Appl. No.: **29/568,669**

(22) Filed: **Jun. 20, 2016**

Related U.S. Application Data

(62) Division of application No. 29/477,419, filed on Dec. 20, 2013, now Pat. No. Des. 759,640.

(57) **CLAIM**

I claim the ornamental design for an overlay, as shown and described.

DESCRIPTION

FIG. 1 is a top perspective view of an overlay, according to a first embodiment;

FIG. 2 is a bottom perspective view of the overlay, according to the first embodiment;

FIG. 3 is a top plan view of the overlay, according to the first embodiment;

FIG. 4 is a side elevational view of the overlay, according to the first embodiment;

FIG. 5 is an opposite side elevational view of the overlay, according to the first embodiment;

FIG. 6 is a bottom plan view of the overlay, according to the first embodiment;

FIG. 7 is a top plan view of the overlay in a folded configuration, according to the first embodiment;

FIG. 8 is a top perspective view of an overlay, according to a second embodiment;

FIG. 9 is a bottom perspective view of the overlay, according to the second embodiment;

FIG. 10 is a top plan view of the overlay, according to the second embodiment;

FIG. 11 is a side elevational view of the overlay, according to the second embodiment;

FIG. 12 is an opposite side elevational view of the overlay, according to the second embodiment;

FIG. 13 is a bottom plan view of the overlay, according to the second embodiment; and,

FIG. 14 is a top plan view of the overlay in a folded configuration, according to the second embodiment.

The evenly dashed broken lines of the various embodiments of the overlay are directed to environment and are for illustrative purposes only; the evenly dashed broken lines form no part of the claimed design.

1 Claim, 6 Drawing Sheets

(58) **Field of Classification Search**

USPC D14/341, 345, 346, 439, 432; D3/201, D3/218, 269, 301, 273, 303; D13/103, D13/107-108
